UNITED STATES PATENT OFFICE.

WILLIAM DIETRICH, OF CHICAGO, ILLINOIS.

CASTING-MACHINE.

1,104,728.

Specification of Letters Patent.

Patented July 21, 1914.

Application filed December 4, 1913. Serial No. 804,778. **REISSUED**

To all whom it may concern:

Be it known that I, WILLIAM DIETRICH, a citizen of the United States, residing at Chicago, in the county of Cook and State 5 of Illinois, have invented a new and useful Casting-Machine, of which the following is a specification.

My invention relates to casting machines for casting rectangular blocks of metal in 10 which the size of the mold for the block can be varied in size, and the objects of my improvements are first, to retain the mold in a rectangular form; second, to make two sides of the mold movable; third, to provide 15 means for retaining the one movable side of the mold in a rectangular position to the balance of the mold while being moved; fourth, to provide sliding blocks on two opposing sides of the mold to assist in forming 20 one movable side of the mold; fifth, to provide means for securing the different sides of the mold in proper position; sixth, to make a neat, cheap and efficient device and other features to become apparent from 25 the description to follow.

As above mentioned my invention pertains to machines for casting rectangular blocks of metal, the blocks being used in the art of printing for securing a page of type 30 into a chase and for any other suitable purpose. In the use of these rectangular blocks it has been found that work is greatly facilitated by forming or casting the blocks as fast as they are needed and after they have 35 served their purpose to recast them into other blocks of different sizes as again required. This eliminates the necessity of keeping a large stock of blocks on hand and the danger of mutilating the blocks by oft 40 handling.

To describe my invention so that others versed in the art to which it pertains can make and use the same I have illustrated it on the accompanying two sheets of drawings forming a part of this specification in which:—

Figure 1, is a plan view of a machine embodying my invention; Fig. 2, is a fragmentary plan view showing one side of the 50 mold moved to an open position; Fig. 3, is a cross sectional view taken on line 3—3 of Fig. 1, and Fig. 4, is a cross sectional view taken on line 4—4 of Fig. 1.

Similar reference characters refer to similar parts throughout the several views.

The mechanism is all mounted on a horizontal metal table 5 of sufficient thickness and which preferably has the depending reinforcing flange 6 at its four edges. The table 5 is rectangular in shape and of any 60 desirable size. Secured rigidly to the top of the table 5, by means of screws 7 or otherwise, are the three metal bars 8, 9 and 10 to form three sides of a rectangle. The bar 8 being located at the front edge of the 65 table 5, the bar 9 being located at the left hand end of the table 5 and the bar 10 being located at the rear edge of the table 5. At the right hand edge of the table 5 is provided a bar 11 forming the fourth side of 70 the rectangle formed by the bars 8, 9, 10 and 11, which is pivotally secured to the rear edge of the table 5 at 12 to swing in a horizontal plane. The free end of the bar 11 is detachably secured in position against the 75 right hand end of bar 8 by a pin 13 fitting snugly into a hole provided therefor in the bar 11 and fits snugly to the table 5 and against the end of bar 8 so that molten metal cannot escape past the same. 80

A bar 14 is mounted to slide freely laterally forward and back on the table 5 and has attached to each end by means of a screw or pin, 15 a rackbar 16 which rack-bars extend rearwardly from the bar 14 85 along beside the bars 9 and 11, through guide-ways 17 provided therefor in the under side of the bar 10 as seen in Fig. 4.

The bar 14 is of such length as to fit between the bars 9 and 11 and lies parallel to 90 the bar 8, and as said bar 14 is moved toward and away from the bar 8 it is retained parallel to the bar 8. The bars 14, 11 and 8 form three sides of the mold into which the molten metal is poured, therefore the bar 95 14 also fits snugly to the table 5 and against the side of bar 11. The bar 14 is moved as desired toward and away from the bar 8 by manipulating the hand wheel 18 which is rigidly secured to the shaft 19 mounted in bearings 20 integral with or mounted on the bar 10. Rigidly mounted on the shaft 19 are the two small gears 21 which are in constant mesh with the rack bars 16 so that as the shaft 19 is rotated the gears 21 will 100 move the rack bars 16 in unison, which of course will also move the bar 14. To secure the bar 14 in any desired position a set screw 22 is provided in one of the bearings 105 20 to take against the shaft 19. It is ob- 110

vious that preventing the shaft 19 from rotating will hold the bar 14 against movement.

The edge of the bar 11 adjacent the bar 14 is graduated at 23 to enable setting the bar 14 at the required distance from the bar 8 which determines the width of the block to be cast.

To determine the length of the block to be cast a pair of adjustable guides are slidably mounted on the bars 8 and 14, the guide 24 is mounted on bar 8 and the guide 25 is mounted on bar 14, and each is constructed like the other with a set screw 26 for securing it in any desired position on its coöperating bar. Each bar 8 and 14 is provided with graduations on one edge at 27 with which the guides 24 and 25 coöperate. The said graduations are spaced exactly the same distances from the bar 11 so that if a rule or other metal piece is laid against the two guides 24 and 25 when they are set at corresponding figures, said rule or other metal piece will be parallel to the bar 11 as indicated at 28. The rule 28 forms the fourth side of the mold into which the molten metal is poured, and the distance between the rule 28 or rather the nearest side of the guides 24 and 25 and the rule 11 determines the length 30 of the block to be cast.

In operation to cast a block of metal of certain dimensions in two directions, the bar 14 is set at the figure on the graduations 23 to correspond to the width of the desired 35 block, and the gages 24 and 25 are set at the figure on the graduations 27 to correspond to the length of the desired block. Care is taken that the free end of the bar 11 is secured in position against the end of the 40 bar 8 by pin 13. A rule 28 of proper length is placed against the two guides 24 and 25; then the molten metal is poured onto the table 5 within the confines of the rule 28 and bars 8, 11 and 14. After the metal has 45 sufficiently hardened, the pin 13 is withdrawn and the free end of bar 11 is swung to the right about the pivot 12, as shown in Fig. 2, and the block of metal is pushed out of the mold to the right. After the cast 50 block is thus removed from the mold the free end of bar 11 is again returned to its position against the end of bar 8, and the machine is in position for casting another block of the same dimensions. The pin 13 is 55 preferably prevented from becoming detached from the table 5 by means of a small chain or cord.

Having thus fully described my invention what I claim as new and desire to secure by 60 Letters Patent of the United States is:—

1. In a device of the class described, a suitable table, a suitable bar rigidly secured on the table at the front edge, a second bar secured rigidly on the table at the left hand edge extending from the first named bar to

the rear of the table, a third bar secured on the table at the right hand edge extending from the first named bar to the rear of the table, a fourth bar slidably mounted on said table parallel to the first named bar and extending from said second named bar at the left to said third named bar at the right and means for moving said fourth named bar laterally toward and away from said first named bar comprising two rack bars connected to said fourth named bar and two gears meshing with said rack bars mounted rigidly on a common shaft.

2. In a device of the class described, a suitable table, a bar rigidly secured to the table at the front edge, a second bar rigidly secured to the table at the left hand edge extending from said first named bar to the rear of the table, a third bar secured to the table at the right hand edge extending from said first named bar to the rear of the table and mounted to swing on a pivot at one end, a fourth bar slidably mounted on said table parallel to said first named bar and extending from said second named bar to said third named bar, a rack bar connected at either end of said fourth named bar and extending laterally therefrom to the rear edge of the table, a shaft at the rear edge of the table, gears rigidly mounted on said shaft in constant mesh with said rack bars, means for rotating the said shaft and means for locking the shaft against rotation.

3. In a device of the class described, a suitable table, a bar rigidly mounted on said table at the front edge, a second bar rigidly mounted on said table at the left hand edge and extending from said first named bar to the rear edge of the table, a third bar pivotally mounted on said table with means for locking it at the right hand edge of said table extending from said first named bar to the rear edge of the table, a fourth bar movably mounted on said table parallel to said first named bar and extending from said second named bar to said third named bar, means for moving said fourth named bar laterally toward and away from said first named bar comprising two rack bars connected to said fourth named bar and a shaft carrying two gears in constant mesh with said two rack bars, a guide block slidably mounted on said first named bar and a guide block slidably mounted on said fourth named bar.

4. In a device of the class described, a suitable table, a bar rigidly mounted on said table at the front edge, a second bar rigidly mounted on said table at the left hand edge and extending from said first named bar to the rear edge of the table, a third bar mounted on the table at the right hand edge extending from said first named bar to the rear edge of the table, a fourth bar slidably mounted on said table parallel to the first

named bar and extending from said second
named bar at the left to said third named
bar at the right, means for moving said
fourth named bar laterally toward and away
from said first named bar and a guide block
slidably mounted on said first named bar.

In testimony whereof, I have signed my

name to this specification in presence of two
subscribing witnesses this 1st day of Decem-
ber 1913, at Chicago, Illinois.

WILLIAM DIETRICH.
